LIQUID-SEALED LIFTER ROOF FOR LIQUID STORAGE APPARATUS

John H. Wiggins, Chicago, Ill.

Application April 5, 1946, Serial No. 660,016

3 Claims. (Cl. 48—176)

1

This invention relates to fluid storage apparatus of the particular type that comprises a tank or equivalent stationary container having a side wall, a "lifter" roof, or vertically-movable roof for said tank, provided with a skirt, dip ring or side wall portion arranged in telescopic relation with the tank side wall, and a liquid seal for said roof, composed of a reservoir extending circumferentially around the tank side wall and containing a liquid sealing medium in which the depending side wall portion of the roof is immersed.

The main object of my present invention is to provide a fluid storage apparatus of the general type or kind above mentioned, which is of such design or construction that a considerable saving is effected in the volume or quantity of the liquid used to seal the roof, and loss of the sealing liquid, due to evaporation and/or absorption, is greatly diminished.

Other objects and desirable features of my invention will be hereinafter pointed out.

I attain the above described results:

(1) By reducing the width of the reservoir for sealing liquid to a fractional part of the width of the sealing liquid reservoir used in a liquid-sealed lifter roof of conventional design;

(2) By constructing the skirt, dip ring or side wall portion of the roof in the form of a limber, circumferentially flexible, ring-shaped member or cylinder; and

(3) By mounting said skirt or side wall portion on the roof in such a manner that, although said parts are connected together by a gas-tight joint, said side wall portion is capable of a limited circumferential movement relatively to the roof, and the roof is capable of a limited radial or sideways movement relative to said side wall portion, in the event the side wall structure of the apparatus goes out of round or the roof is subjected to wind pressures tending to shift it sideways or laterally relatively to the stationary tank or container of the apparatus.

Figure 1 of the drawings is a vertical transverse sectional view of a fluid storage apparatus embodying my present invention.

Figure 2 is an enlarged fragmentary vertical sectional view, showing the roof in a raised position.

Figure 3 is a similar view, showing the roof in its lowermost position; and

Figure 4 is a sectional view, taken on the line 4—4 of Figure 2, looking in the direction indicated by the arrows.

In the drawings, A designates the side wall 55

2

portion of a tank that is adapted to be used for storing a fluid, usually gasoline or some other highly volatile material, B designates a lifter roof or vertically-movable roof for said tank, C designates a depending side wall portion, skirt or dip ring on said roof, arranged in telescopic relationship with the tank side wall, D designates an annular reservoir, herein illustrated as being attached to the side wall A of the tank adjacent 10 the top edge of same and proportioned so that the annular outer wall of said reservoir will surround the depending skirt C on the roof, x designates a liquid sealing medium in the reservoir D, such, for example, as fuel oil in which the skirt 15 C is immersed, and E designates as an entirety a roof supporting structure inside of the tank, composed of a center post that supports a plurality of radially-disposed rafters, whose outer ends are attached to the tank side wall A at the top edge 20 of same.

Instead of forming the skirt or depending side wall portion of the roof from a relatively stiff, annular member that has little or no circumferential flexibility, and which is rigidly connected to the roof, as has heretofore been the universal practice, I construct the side wall portion C in the form of a limber ring or cylinder that is circumferentially flexible throughout its entire area, and I suspend said member C from the 25 underside of the roof B by a means, which, in addition to maintaining a gas-tight joint between said parts, makes it possible for the roof to have a limited radial movement or lateral movement relatively to the member C, and makes it possible for said member C to have a limited circumferential movement relatively to the roof. In the preferred form of my invention herein illustrated, the means just mentioned comprises a plurality of hangers or links 1 on the underside of the roof, 30 connected at their upper ends by pivots 2 to lugs 3 on the roof, and connected at their lower ends by pivots 4 to lugs 5 on the exterior of the side wall portion C, the hangers 1 being spaced apart from 6 to 12 ft. around the circumference of the 35 peripheral portion of the roof B. Said means also comprises an annular-shaped, flexible sealing element F, preferably made of gas-tight fabric, attached at its lower end by circumferentially-flexible clamping bars 6 to the top portion of the member C, and attached to its upper end by means of clamping bars 7 to the roof B. The pivotal connections between the links 1 and the roof B and between said links and the side wall portion C, are loose enough to permit said links to swing radially and also swing slightly to the left and right, as in-

dicated by broken lines in Figure 4, thereby causing the side wall portion C, in effect, to be floatingly mounted or suspended from the underside of the roof B. Accordingly, in the normal functioning of the apparatus, if there is a tendency for the roof to move sidewise or radially relatively to the side wall A of the tank, or if there is a tendency for the side wall portion C of the roof to move circumferentially relatively to the top portion of the roof, the hangers or links 1 permit or provide for limited movement of said parts in the directions mentioned. As shown in the drawings, the flexible sealing element F has sufficient slack or fullness to provide for the above mentioned relative movement between the roof B and the side wall portion C, and to prevent the weight of said side wall portion from being imposed on the sealing element.

By constructing the skirt or side wall portion C in the form of a limber, circumferentially flexible member and attaching said member to the roof B in the manner above described, I am able to reduce the width of the reservoir for the sealing liquid from the conventional width of approximately 10 to 14 inches, to approximately 1½ inch. Hence, my improved apparatus requires only about $\frac{1}{7}$ to $\frac{1}{6}$ as much sealing liquid as prior liquid-sealed lifter roofs, thereby effecting a considerable saving in the volume or quantity of sealing liquid, and thus reducing the cost of building and maintaining the apparatus. Moreover, as the area of the sealing liquid is only a small fraction of the area of the surface of the sealing liquid in a liquid-sealed lifter roof of conventional design, loss of sealing liquid, due to evaporation and absorption, is greatly diminished. In other words, in my improved apparatus there is only a relatively small body of sealing liquid on the inner side of the side wall portion C of the roof, that can absorb vapors from the material stored in the tank A, because the width of the space between the inner side wall of the reservoir D and the inside face of the depending skirt C of the roof, is usually not more than approximately 1 inch, whereas, in a liquid-sealed lifter roof of conventional design, the width of said space is several inches. Also, there is a relatively small body of sealing liquid on the air side, or on the outer side of the skirt C, that is exposed to air, and thus subject to evaporation. In fact, in my improved apparatus the side wall portion or skirt C of the roof and the outer wall of the reservoir D, are preferably so proportioned that when the apparatus is being erected, the skirt C is arranged substantially in contact with the inside face of the outer wall of the reservoir D, which outer wall is constructed in the form of a substantially stiff, annular member. If desired, a flexible wiper G can be attached to the top edge of the outer wall of the reservoir D, so as to act on the outer surface of the side wall portion C of the roof, and thus remove from said portion and return to the

reservoir, any particles of liquid that adhere to the side wall portion when the roof rises and falls.

As previously stated, a fluid storage apparatus 5 of the construction above described, is an improvement on prior apparatus of the kind equipped with a liquid-sealed lifter roof, in that it requires only a small fractional amount of the sealing liquid employed in prior apparatus, it 10 greatly reduces the loss of sealing liquid resulting from evaporation and/or absorption; and although the sealing liquid reservoir consists of only a narrow trough whose outer wall is in very close relationship with the depending skirt or 15 side wall portion of the roof, the roof can rise and fall and even assume a slightly tilted or angular position, without causing the skirt of the roof to bind in the reservoir, due to the fact that said skirt consists of a circumferentially flexible cylinder that is floatingly suspended from the underside of the roof by a means which comprises a curtain-like, flexible sealing element that maintains a gas-tight joint between the roof and its side wall portion and at the same time permits 20 25 said parts to have a limited radial and circumferential movement relatively to each other.

Having thus described my invention, what I claim as new and desire to secure by Letters Patent is:

- 30 1. A fluid storage apparatus, comprising a tank having a side wall provided with a reservoir that is adapted to contain a sealing liquid, a vertically-movable roof for said tank, a depending skirt on said roof projecting downwardly into said reservoir, hangers that suspend said skirt from the roof, and a flexible, gas-tight element for sealing the joint between the roof and said skirt, said hangers being constructed so as to permit said skirt to move circumferentially a limited distance relatively to the roof.
- 35 2. A fluid storage apparatus, comprising a tank having a side wall, a vertically-movable roof for said tank, a skirt projecting downwardly from the roof, a narrow trough on the side wall of said tank disposed so as to receive said skirt and adopted to contain a sealing liquid, a flexible sealing element for producing a gas-tight joint between the roof and skirt, and a pivotal connection between said skirt and roof.
- 40 3. A fluid storage apparatus, comprising a tank having a side wall provided with a reservoir that is adapted to contain a sealing liquid, a vertically-movable roof for said tank, a depending skirt mounted on the underside of the roof by oscillating hangers a flexible sealing element between the roof and skirt, said skirt projecting downwardly into said trough in close proximity to the outer wall of said trough, and a wiper on the outer wall of said trough that bears against the outer surface of said skirt.
